UNITED STATES PATENT OFFICE.

JOHN W. FRAZEE AND ANDREW J. THOMAS, OF KANSAS CITY, MISSOURI

COMBINED COOLER AND FILTER.

SPECIFICATION forming part of Letters Patent No. 334,426, dated January 19, 1886.

Application filed June 11, 1885. Serial No. 163,407. (No model.)

To all whom it may concern:

Be it known that we, JOHN W. FRAZEE and ANDREW J. THOMAS, citizens of the United States, residing at Kansas City, in the county 5 of Jackson and State of Missouri, have invented certain new and useful Improvements in a Combined Cooler and Filter, of which the following is a specification, reference being had to the accompanying drawing.

10 This invention has relation to a combined water cooler and filter; and it consists, substantially, in the same as constructed, and in the particular combinations of parts to be hereinafter distinctly described, and pointed 15 out in the claims.

The objects of our invention are to supply a cooler and filter that may be constructed at small cost, one in which comparatively few parts are employed, and one by which water 20 or other liquid may be cleansed of its impurities in a thorough and rapid manner. These objects we attain by the device shown in the accompanying drawing, wherein is represented in vertical sectional elevation a combined cooler and filter embodying our improvements.

The main design or result aimed at in the operation of our invention is to have the volume of water which the vessel contains destroyed of its equilibrium, and then cause it, 30 in again seeking to establish its level or equilibrium, to pass through the several filtering media arranged in the tubes, as hereinafter described, whereby it is thoroughly cleansed 35 of all impurities.

In the accompanying drawing, A represents an upper tank or vessel fitting in the top of a lower vessel, B. The tank A is provided with an additional or inner wall, a, the space 40 between the two being filled with any suitable packing or non-conducting material, b, and the said tank is provided with a lid or cover, c, fitting in the top thereof, as shown. In the bottom of the tank is formed an opening, d, 45 around which extends a screw-threaded flange, e, to which is fitted a cap, f, having a series of perforations, g. Connecting with the opening d from beneath is the upper end of the filtering-tube C, the same branching off to one side, 50 as shown, thence downward and upward, and

again downward and upward, the extremity thereof being fitted with a perforated cap, h. The vertical portions of this continuous tube are connected at top and bottom by horizontal sections i j k, and extending downward 55 from the two last-named sections are threaded flanges l m n, each having a removable cap. These flanges communicate with the interior of the filtering-tube, and the filtering material may be removed at any time by simply unscrewing the caps; and so, also, in this way may the tube be cleaned when desired. In the neck of the tube communicating with opening d we arrange a sponge, o, and we fill the horizontal section of tube j with charcoal and hair 60 felt, the charcoal extending up a short distance in the vertical section 1, and the hair felt extending up in like manner into the section 2. Then in the lower extremity of the section 3 we arrange a quantity of asbestos, and beneath 70 that in the horizontal section k is arranged some large gravel, all as shown. In this manner the water will first enter the filtering-tube through the perforations in cap g, thence pass through the sponge and flow down and pass 75 through the charcoal and hair felt in the lower extremity of the sections 1 2, rise up in the latter section, thence down into section 3, through the hair felt and gravel at the bottom thereof, and finally upward in section 4, and 80 issue through the perforations in cap h, in a thoroughly filtered condition, to be drawn off at any time through the cock p. By placing a suitable quantity of ice in the tank A the water will be cooled. 85

Having thus described our invention, we claim as new and desire to secure by Letters Patent—

1. In a combined cooler and filter, the combination of an upper tank having double walls, 90 a lower tank, and a filtering-tube communicating with the former at the bottom and extending down into the latter, substantially as described.

2. In a combined cooler and filter, the combination of an upper tank having double walls and provided in its bottom with an opening surrounded by a threaded flange having perforated cap, of a filtering-tube composed of a 95 number of vertical sections united at their two 100

ends by horizontal sections and provided at its extremity with a perforated cap, and the lower tank, B, said filtering-tube being provided with layers of the several-named filtering media, substantially as described.

3. The combination of the tanks A and B, constructed as described, and the filtering-tube C, constructed of the vertical sections 1 2 3 4, and horizontal sections *i j k*, and provided

with the lower capped flanges, *l m n*, all as set forth.

In testimony whereof we affix our signatures in presence of two witnesses.

JOHN W. FRAZEE.
ANDREW J. THOMAS.
